PITCHER

Ronald R. Cryer, 1620 Magnolia Lane,
Fort Wayne, Ind. 46825

Filed Mar. 7, 1973, Ser. No. 338,646

Term of patent 14 years

Int. Cl. D10—04

U.S. Cl. D7—50

FIG. 1

FIG. 2

FIG. 3

FIG. 4

FIG. 5

FIG. 1 is a side view of a pitcher showing my new design;

FIG. 2 is a front view thereof;

FIG. 3 is a top plan view thereof;

FIG. 4 is a back view thereof; and

FIG. 5 is a bottom view thereof.

The side opposite to that illustrated in FIG. 1 is identical in shape.

I claim:

The ornamental design for a pitcher, substantially as shown and described.
